UNITED STATES PATENT OFFICE

93,828

DESIGN FOR A WINDOW SHADE CORD RING

Samuel J. Johnson, Cincinnati, Ohio, assignor,
by mesne assignments, to Clopay Corporation,
Baltimore, Md., a corporation of Maryland

Application October 20, 1932, Serial No. 45,423

Term of patent 14 years

To all whom it may concern:

Be it known that I, SAMUEL J. JOHNSON, a citizen of the United States, residing at Cincinnati, in the county of Hamilton and State of Ohio, have invented a new, original, and ornamental Design for a Window Shade Cord Ring, of which the following is a specification, reference being had to the accompanying drawing, forming a part thereof.

Figure 1 is a perspective view showing the design of the window shade cord ring.

Figure 2 is a central sectional view of the cord ring.

I claim:

The ornamental design for a window shade cord ring as shown.

SAMUEL J. JOHNSON.
